UNITED STATES PATENT OFFICE.

JOSEPH F. HIRT, OF CHICAGO, ILLINOIS.

DRY-KILN.

1,385,451.

Specification of Letters Patent. Patented July 26, 1921.

Application filed April 20, 1920. Serial No. 375,212.

To all whom it may concern:

Be it known that I, JOSEPH H. HIRT, a citizen of the United States, residing at Chicago, in the county of Cook and State of Illinois, have invented certain new and useful Improvements in Dry-Kilns, of which the following is a specification, reference being had therein to the accompanying drawing.

The invention relates to drying rooms for 10 lumber, veneers, glue joints in panel cores, completed panels and other wooden articles as well as coatings of varnish, stains, fillers, enamels and paints on articles of furniture, vehicles, interior decoration, etc. However, 15 the invention is particularly adapted for use in connection with drying rooms commonly known as dry kilns.

Apparatus of this character has heretofore been constructed in such manner as 20 would expose the product to be dried directly to the heating units located either horizontally underneath or vertically along the sides or center of the kiln. This invariably has the effect of evaporating the necessary humidity in the immediate vicinity 25 of said heating units and to a lesser degree throughout the kiln. This necessarily being an uneven drying, it is obvious that considerable waste of material is occasioned; therefore 30 it is the principal object of the invention to provide a kiln wherein the material therein will be uniformly dried and at the same time dried quicker than in the common type of kilns now in use, by providing 35 said uniform drying it is obvious that the waste of material incident to irregular drying is eliminated.

A further object is to provide a kiln having a drying chamber therein and to provide 40 means whereby a circuit of air, which has been heated before entering the drying kiln is maintained through the drying kiln from the top of the kiln downwardly, said air as it enters the drying chamber being supplied 45 with humidity and being thoroughly mixed with the air before entering the drying chamber. Also to provide means whereby fresh air may be added to the recirculating air for supplying oxygen, said fresh air 50 being supplied to the recirculating air at a point so that it will be thoroughly heated and mixed with the recirculating air before it enters the drying chamber.

A further object is to provide means

whereby the fresh air entering the heating 55 chambers may be controlled in volume and location in the kiln, also to provide means whereby the amount of humidity supplied to the recirculating air may be controlled in amount and in various locations.

A further object is to provide a kiln so constructed that the same may be used as what is known as a box kiln or as what is known as progressive type of kiln.

A further object is to provide ducts of 65 communication between the drying chamber and the heating chamber whereby as the recirculating air passes through the drying chamber said ducts will admit some of the air to the heating chambers which will set 70 up an action which will cause the circulating air in the drying chamber to extend to all parts thereof so that the drying will be uniform.

A further object is to provide curtains adjacent the sides of the entrance passage to the drying chamber, which curtains will cause the recirculating air to pass downwardly through the material within the drying kiln at a substantially central point 80 thereof and spread outwardly uniformly through the drying chamber.

With the above and other objects in view the invention resides in the combination and arrangement of parts as hereinafter set 85 forth, shown in the drawings, described and claimed, it being understood that changes in the precise embodiment of the invention may be made within the scope of what is claimed without departing from the spirit 90 of the invention.

In the drawings:—

Fig. 1 is a perspective sectional view, transversely through the kiln.

Fig. 2 is a longitudinal sectional view 95 taken on line 2—2 of Fig. 1.

Fig. 3 is a transverse vertical sectional view through the kiln showing a stack of lumber disposed therein.

Fig. 4 is an end view of the kiln showing a 100 closure therefor.

Fig. 5 is a perspective detail view of the deflecting curtains for engaging the top of the material disposed in the drying kiln.

Fig. 6 is a perspective detail view of a 105 portion of the humidity supplying pipe and controlling means for controlling the amount of humidity supplied to the air.

Fig. 7 is a perspective view of a portion of the humidity supply pipe showing the control valves and the operating rods in position to be secured thereto.

5 Fig. 8 is a detail perspective view of the connection between the controlling rods and the valve stems.

Fig. 9 is a sectional view through one of the material engaging curtains.

10 Fig. 10 is a side elevation of a series of the sections from which the curtains are formed.

15 Fig. 11 is a detail view of one of the humidity supplying sections showing the controlling rod connected thereto.

Fig. 12 is a perspective view showing one of the independent dampers for controlling the amount of fresh air supplied to the heating chambers.

20 Fig. 13 is a perspective view of one of the sliding dampers for controlling the passage of air from the drying chamber to the atmosphere.

25 Fig. 14 is an enlarged sectional view through a portion of the top of the kiln showing the position of the controlling rods for controlling the humidity supply sections and also showing a concaved surface for deflecting the humidity as it leaves the pipe.

30 Referring to the drawings, the numeral 1 designates a kiln and 2 a drying chamber therein. Within the side walls 3 of the drying chamber 2 are heating chambers 4, in which heating chambers heat-units 5 are disposed, said heating units may be separately controlled from the outside of the kiln so that the amount of heat radiated may be controlled. The side walls 3 of the drying chamber 2 extend upwardly from the 35 floor 6 thereof, and are provided with inwardly extending members 7 which extend toward each other and are spaced from the top 8 of the kiln, thereby forming passages 9 which merge into each other substantially 40 centrally of the drying chamber as at 10. The object of providing the space 10 is to provide means whereby as heated air passes upwardly and inwardly through the 45 passages 9, it will pass downwardly into the drying chamber at a point substantially centrally thereof, the purpose of which will 50 presently appear. Disposed above the space 10 is a longitudinally disposed concave deflecting surface 11 against which surface 55 steam is projected from banks of valves 12, which banks of valves are controlled by means of control rods 13, the ends of which are disposed outside of the kiln and form means whereby the amount of humidity sup- 60 plied to the circulating air may be controlled and varied as desired in various parts of the kiln. Suspended below the humidity pipe 14 is a longitudinally disposed trough 65 which trough collects and carries off con- densation from the steam and may discharge

at any point outside of the kiln. The floor 6 is provided with a series of passages of communication 16, which passages communicate with the lower ends of the heating chambers 4. Fresh air is admitted to the 70 heating chambers 4 through longitudinally disposed air ducts 17, preferably disposed beneath the flooring 6 and at both sides of the kiln. The outer ends of the air ducts 17 may communicate with the atmosphere 75 at any point desired, however they preferably communicate with the atmosphere at the ends of the kiln. Extending upwardly from and in communication with the fresh air ducts 17 are ducts 18, the upper ends of 80 which discharge into the heating chambers 4, at a point substantially two thirds of the way from the bottom of the heating element, however, it is to be understood that these ducts may communicate with the heating 85 chambers at any point desired. Interposed between the vertical ducts 18 and the longitudinal ducts 17 are slideable dampers 19, controlled by rods 20 which extend to a point outside of the kiln. By means of 90 dampers 19 it will be seen that the amount of air passing from the ducts 17, through the vertical ducts 18 to the heating elements may be controlled and varied. Each duct 18 by being independently controlled as to 95 the amount of air entering the heating chambers 4, it will allow the temperature in any particular point at the kiln to be controlled, thereby providing a kiln of what is known as the box or compartment type, and 100 also a kiln which may be used as what is known as the progressive type. It will also be seen that by providing means whereby humidity may be supplied in varying quantities at various points, through separably 105 controlled mechanisms, the amount of humidity supplied to any particular portion of the kiln may be varied as desired.

Extending longitudinally of the kiln and disposed between the floors 6 is a beam 21, the sides of which are spaced from the adjacent sides of the flooring 6. Said spacing of the beam 21 allows the air in its recirculation to pass outwardly to the heating chambers 4. The air enters through the ducts 17, passes upwardly through the ducts 18 and enters the heating chambers 4. The air is then heated, and being light rises upwardly and passes inwardly through the passages 9, thence downwardly through the 110 passage 10. However, immediately before the hot air passes through the passage 10 it is supplied with humidity from the humidity pipe 14. After the hot air is supplied with humidity it passes downwardly 115 through the material in the drying chamber and enters the passages of communication 16 to the heating chambers 4 where it is again heated. However as the air passes upwardly through the heating chamber 4 120

65 125 130 135

it will be seen that the ducts 18 will supply fresh air to the recirculating air, thereby providing oxygen. Disposed in the walls 3 are openings 22, which openings 22 communicate with the heating chambers 4. The purpose of the openings 22 is that is has been found that when a recirculation is used for drying purposes, that the heat will not be uniform throughout the drying chamber 10 unless means is provided for causing the recirculating air to be drawn in the direction of the sides of the drying chamber. By providing the openings 22 it will be seen that the heated air in the heating chambers 4 will cause a circuit of air to flow through openings 22 thereby causing the recirculating air to be drawn to the sides of the drying chamber so that the air will be uniformly distributed throughout the drying chamber. 15

20 Extending outwardly from the bottom of the kiln and preferably disposed beneath the flooring 16 thereof are exhaust ducts 23, the inner ends of which are in communication with the lower side of the drying chamber 25 as at 24. It will be seen that during the recirculation that a certain amount of the damp air will pass outwardly through the exhaust ducts 23, which ducts preferably discharge as at 25^a at points above the kiln 30 proper. The openings 24 are controlled by means of slideable dampers 26, which dampers are controlled by means of rods 27, which rods have their ends disposed at a point outside of the kiln and are independently controllable, thereby allowing the amount of moist air which naturally falls to the bottom of drying chamber to be controlled in its passage to the atmosphere. 35

By referring to Fig. 3 it will be seen that 40 lumber has been stacked on trucks and placed in the drying chamber. Lumber when placed in a drying kiln is as a rule uneven in sizes and not closely packed, the layers being spaced from each other by spacing strips as shown at 28 in Fig. 5. It will be seen by referring to Fig. 5 that various sized lumber is shown and that their edges are not in engagement with each other thereby leaving space between the pieces of lumber. 45 When the lumber is in this condition, it will be seen that the recirculating air, after being supplied with humidity will pass downwardly centrally and pass between the boards and that by allowing the passage 50 of a portion of the air through the openings 22 the recirculating air will be uniformly distributed in the drying chamber, thereby thoroughly and uniformly drying the lumber throughout its entire length and width. 55

60 However to compel the recirculating air to pass through the pile of lumber, longitudinally disposed curtains 29 are disposed on each side of the opening 10. Curtains 29 may be of any number desired, however, it is 65 preferable on account of the uneven surface of the top of the stack of lumber that said curtains 29 be formed in sections 30, each section having its lower edge provided with a weight 31. The weights hold the sections 30 in engagement with the top of the stack 70 of lumber and prevent the air from passing in any direction except downwardly through the lumber. It will also be seen that by providing the spaced curtains deflecting walls are provided which actually contacts 75 with the product in the drying chamber, thereby assuring the passage of the recirculating air through the product within the kiln chamber. From the above it will be seen that a kiln is provided wherein the 80 heated air is circulated with proper velocity, and one wherein a separately controlled amount of fresh air is admitted to the heated recirculating air, thus replenishing the recirculating air with fresh air only as it is absorbed by the product being dried. It will also be seen that humidity can be admitted in separately controllable quantities from the various banks of humidifiers throughout the kiln, thereby allowing said humidity to be 85 thoroughly mixed with the recirculating elements, before entering the drying chamber. By providing a kiln having the fresh air ducts spaced through its length, each separately controlled and having its exhaust 90 ducts spaced throughout its length each separately controlled, it will be seen that all of the drying elements may be controlled to cause and maintain equal proportions of the said drying elements throughout the entire area of the drying chamber thus providing a compartment or box type kiln, is controllable to meet the severe weather conditions when any one end is exposed, at which time it is necessary to vary the temperature and humidity at the exposed end or; as the heating units are each separately controlled, the fresh air intake ducts are separately controlled, the humidifiers each separately controlled, and the exhaust ducts 100 105 separately controlled, it will be readily seen that conditions within the drying chamber proper can be made variable throughout the length of the kiln, thus causing conditions to exist complying accurately to the conditions 110 maintained in a compartment or box type kiln, and in this case providing what is commonly known as a progressive type kiln. 115

The invention having been set forth what is claimed as new and useful is:— 120

1. A kiln having a drying chamber and a heating chamber, means for circulating air through said chambers, means whereby fresh air is admitted to the circulating air at a point where it will pass through the heating chamber before entering the kiln chamber thereby thoroughly mixing and heating the additional fresh air with the recirculating air, before entering the drying chamber, means for supplying humidity to the air be- 125 130

fore it enters the drying chamber and means for varying the amount of humidity supplied to various portions of the kiln.

2. A kiln having a drying chamber and a heating chamber, means for circulating air through said chambers, means whereby fresh air is admitted to the circulating air in controlled amounts at a point where it will be compelled to pass through the heating chamber before entering the kiln chamber thereby thoroughly mixing and heating the additional fresh air with the recirculating air before it enters the drying chamber, means for supplying humidity to the air at various locations before it enters the drying chamber, said humidity being supplied to the air at the top of the chamber, and means whereby the amount of humidity supplied to the air may be separately controlled in various portions of the kiln from without the kiln.

3. A kiln having a drying chamber and a heating chamber, means for circulating air through said chambers, means whereby fresh air may be admitted to the recirculating air in separately controllable amounts and at points where it will pass through the heating chamber before entering the drying chamber, means whereby humidity may be supplied to the recirculating air in separately controllable amounts in various portions of the kiln as it enters the drying chamber, means whereby a predetermined amount of the circulating air may be exhausted to the atmosphere from the bottom of the drying chamber and passages of communication between the drying chamber and the heating chamber whereby the circulating air in the drying chamber will be caused to be uniformly distributed in the drying chamber during its recirculating.

4. A kiln comprising a drying chamber and heating chambers disposed to the sides of the drying chamber, ducts for admitting fresh air to the heating chambers, said heating chambers being in communication with the drying chamber substantially in the center at the top thereof and substantially in the center at the bottom thereof, the lower ends of the heating chambers being in direct communication with the drying chamber at its lower side, heating units disposed in the heating chambers, ducts for supplying fresh air in separately controllable quantities to various locations within the heating chambers where it is mixed and heated, caused to circulate upwardly, inwardly, downwardly through the drying chamber and recirculate through the communications between the lower ends of the heating chambers where it is again heated and supplied with additional fresh air and recirculated, ducts in the side walls of the drying chamber and in limited direct communication with the heating chambers and forming means for causing the circulating air to be uniformly

distributed in the drying chamber, and separately controllable ducts whereby a predetermined amount of the circulating air may be exhausted to the atmosphere from spaced points adjacent the bottom of the drying chamber.

5. A kiln comprising a drying chamber having heating chambers located at its sides, inwardly extending passages of communication between said heating chambers and the drying chamber at the upper end thereof, inwardly extending passages of communication between the lower ends of the heating chambers and the bottom of the drying chamber, means for admitting fresh air to the heating chambers through separately controlled ducts, whereby fresh air may be applied to the recirculating air, means for recirculating this mixture up between the heating chambers and thence through the drying chamber, downwardly extending longitudinally disposed curtains carried by the upper walls of the drying chamber and adapted to engage the top of the material in the drying chamber so as to deflect the recirculating air through the material, said curtains being of sufficient length and weighted at their bottoms, thereby compensating for the varying heights of the products.

6. A kiln comprising a drying chamber having heating chambers located at its sides, inwardly extending passages of communication between said heating chambers and the drying chambers, inwardly extending passages of communication between the lower ends of the heating chambers and the bottom of the drying chamber, means for admitting fresh air to the heating chambers whereby fresh air may be supplied to the recirculating air as it passes through the heating chambers thereby thoroughly mixing the elements before they enter the drying chamber, means for admitting humidity to the recirculating air before it enters the drying chamber, substantially longitudinally disposed curtains carried by the top wall of the drying chamber and having their lower ends disposed adjacent the top of the material therein for deflecting the recirculating air downwardly through the material, ducts in the side walls of the drying chamber whereby the circulating air will be caused to be uniformly distributed in the drying chamber and passages of communication between the drying chamber and the atmosphere whereby a portion of the circulating air may pass to the atmosphere.

7. A kiln comprising side, top and bottom walls, spaced walls adjacent the side walls and adjacent the top wall, an opening in the top spaced wall substantially centrally thereof, heating elements disposed between the side spaced walls, intake ducts discharging adjacent the heating elements for heat-

- ing the air before it enters the kiln chamber, and means whereby the air will recirculate between the spaced walls and the kiln chamber and exit from the bottom of the kiln 5 chamber substantially centrally thereof.
8. The combination with a kiln having a drying chamber therein, of inverted L-shaped chambers located at the sides of the drying chamber, heating elements in the 10 substantially vertical portions of said heating chambers, duct means for supplying fresh air to said substantially vertical portions, the horizontal portions of said L-shaped chambers extending toward each 15 other and disposed over the drying chamber and having their ends spaced apart, thereby providing an entrance passage to the drying chamber substantially centrally thereof, controllable means for admitting humidity to 20 the air as it enters the drying chamber, and duct means whereby the recirculating air will leave the drying chamber at its bottom and substantially centrally thereof.
9. In a kiln of the character described 25 comprising means whereby a controlled supply of fresh air is admitted at a point within the heating chamber, the air heated and recirculated through a drying chamber and supplied with fresh air during its circuit at 30 a point within the heating chamber, said recirculating air entering the upper end of the drying chamber substantially centrally thereof and leaving the lower end of the

drying chamber at a point substantially centrally thereof. 35

10. A kiln having a drying chamber and a heating chamber, means for circulating air through said chambers, means whereby the circulating air will enter the drying chamber substantially centrally at its top and exit 40 from said drying chamber substantially centrally at its bottom, duct means whereby fresh air may be admitted to the heating chamber through spaced ducts, and means for separately controlling the inflow of fresh 45 air from each duct, thereby admitting additional fresh air to the circulating air in controllable quantities as desired.

11. A kiln having a drying chamber and heating chambers, means for circulating air 50 through said chambers, means whereby fresh air may be admitted to the circulating air at points where it will pass through the heating chambers before entering the drying chamber, said heating chambers being located on 55 each side of the drying chamber, the upper and lower ends of the heating chambers being in communication with the drying chamber at points substantially centrally thereof, and ducts in the side walls of the drying 60 chamber adjacent their lower ends and in direct communication with the heating chambers.

In testimony whereof I hereunto affix my signature.

JOSEPH F. HIRT.
